(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front elevational view of a display screen or portion thereof with graphical user interface showing our new design.

The broken lines showing the outer border of the display screen or portion thereof in the drawing and the interior features of the graphical user interface in the drawing form no part of the claimed design.
